[57] **CLAIM**

The ornamental design for a universal slip-in seat for stand-up jet ski, as shown and described.

DESCRIPTION

FIG. 1 is a top and rear perspective view of a universal slip-in seat for stand-up jet ski showing our new design; FIG. 2 is a rear elevational view thereof, the broken lines illustrating a jet ski are for illustrative purposes and form no part of the claimed design; FIG. 3 is a front elevational view; FIG. 4 is a side elevational view, the opposite side being a mirror image thereof; FIG. 5 is a bottom plan view; and, FIG. 6 is a top plan view thereof.

FIG. 1

FIG. 2

FIG. 3

FIG. 4

FIG. 5

FIG. 6
